Charles H. King & Son, N.Y.

Other Patent

The whole of force in their Valley, and making good of his own
Commanding a description in the way, the via Secunda, Longissima, of
his improvement in Creek Step, ...

To all whom these presents shall come, be it known that, Charles Mr King of Ireland, in the County of Cork and County of Tipperary have issued
late a suggested improvement in the form of Coast Charts and that
the following is a full and exact description of the Constitution and operation
of the said improvement as issued and improved by me.

My improvement in the form of Coach Steps is in
kinda and calculated to add to their strength and durability. This is effected
by giving the joint a syne with greatest room or double bearing. When a step
of wood form is subjected to such a single projection as one end of each side
piece is to only support to keep the same from their proper position and to
bear the weight of the person using it. And as this support is necessarily very near
the center of the joint and the single edge of the step frequently very considerate
and projecting are very liable to be broken off which renders the step useless. In
addition to the projecting or bearing upon the back edges of the horizontal side
pieces of the upper steps which rest against the back edges of the perpendicular
pieces to which they are attached, I propose to make strong projections from the
back edges of the perpendicular pieces to receive the upper ends of the projections
on the horizontal pieces which will render it impossible for the step to give way
and/or both bearings should break off at the same time. This from will more
than double the strength of the joint without adding any thing of weight, and to the
labor of making it, or to weight the wood and iron joints are strengthened
in the same way only the second bearing at the joint is given on the horizontal pieces
that is done by my invention and is which I take a patent in the projection or bear-
ing upon the upper pieces of the step, nothing being the only thing between they
digging into them to secure and hold them in their proper position.
